PAPER MATCH PACKAGE

James J. Neville, Philadelphia, Pa.

Application November 24, 1936, Serial No. 112,476

2 Claims. (CL 206—29)

This invention relates to improvements in paper match packages of the book type and has for its primary object the provision of such a package or container in which the hazard of setting off the bundle of matches in the package when striking a match on the striker means of the package is overcome.

More specifically, it is an object of my invention to provide a match package of the book type in which the striker means is so located that the cover flap of the book must be closed to enable striking a match and in which means is provided for holding the cover closed when the match is being struck.

Another object resides in the provision of means for holding the cover closed adapted to be tucked into place upon pressure on the cover when closing it.

I also aim to increase the space available for advertising purposes or the like without increasing the size of the package over that now generally employed as standard.

How the foregoing, together with such other objects and advantages as may hereinafter appear or are incident to my invention, are realized, is illustrated in preferred form in the accompanying drawing, wherein—

Figure 1 is a perspective view of a match package embodying my invention;

Figure 2 is an enlarged cross-section of Figure 1;

Figure 3 is a fragmentary enlarged elevational view of the lower right-hand portion of the package looking toward the right in Figure 2 and with the cover flap removed; and

Figure 4 is a cross-section of the lower portion of the package with the cover flap shown ready to be snapped into closed position by pressure.

The match package comprises a card 3 folded to provide a back 4, a cover flap 5 and a lower or match retaining flap 6. A bundle or strip of matches 7 is secured in the package by means of a staple 8 passing through the back 4, the base portion of the bundle of matches, and the retaining flap 6. The construction as thus far described in general is well known in book matches.

Referring now to my improvements, it is to be observed that the cover flap 5 extends downwardly to the bottom edge of the package so that it laps over or covers the retaining flap 6 as distinguished from the usual construction in which the cover ends short of this lower edge so that it may be tucked slightly in back of the retaining flap and expose the retaining flap which is provided with striker material, such as emery, on its

outer face. It is intended in this known form of book match that the user tuck the cover in back of the retaining flap when striking a match on the striker strip, and even though a reminder of this is printed on the cover, it is not always heeded. This carelessness has resulted in serious injury to the user.

I propose to overcome this hazard by providing the striker material or strip 9 on the outer face of the cover flap and preferably on the extended portion abovementioned. With the striker surface so located the user must close the cover to get backing support from the package when striking a match, and thus the matches in the package are automatically covered so to speak.

In order to hold the cover in its closed position I provide catch means at the inside of the cover flap which I have illustrated in the form of a folded strip 10 secured to the cover flap as by means of a staple 11. This strip or tab 10 is adapted to engage in back of the retaining flap 6 when the cover is pressed into closed position. This will be seen from inspection of Figure 4 in which the cover flap 5 is in position ready for the application of pressure whereupon the lower edge 12 of the tab 10 will ride over the upper edge 13 of the retaining flap 6 with snap action and then catch or tuck itself in back of the flap 6 as shown in Figure 2 to hold the cover closed. In this connection it is pointed out that the upper edge portion 13 of the retaining flap normally lies clear of the match bundle, i. e., in the position shown in Figure 2, so that after the catch rides over the upper edge of the retaining flap the flap will spring out and the catch will readily tuck itself in back thereof.

By referring to Figure 3, it will be noted that the roots 14 of the matches are located some distance above the upper edge 13 of the retaining flap so that when matches are torn off there will be no interference with the tucking action above described due to the projection of ragged edges caused by tearing off the matches. If the roots were coincident with the upper edge 13 of the retaining flap, these ragged edges would be very apt to cause interference, preventing the tab from readily being tucked into place.

It is also to be observed that a large area is left available above the striker strip on the cover for the printing of advertising matter or the like and, in fact, this area is equal to that provided in known book matches because the striker strip is provided on the extended portion of the cover. Also since I do not have a striker surface on the

exposed face of the retaining flap 6, this provides space for additional effective advertising.

The cover closes more easily and accurately. It can be manipulated by one hand and just as easily with gloves. The tucking action is positive, the closure being effected merely by pressure; and the cover does not slip out. The cushioning of the striker strip reduces match sparking.

I claim:

- 10 1. A match package of the book type comprising a card having a match retaining flap and a cover flap having its free end portion extended to cover said retaining flap, striker means on the outer face of the cover flap at said extended portion, and a folded tab secured on the inner face of said cover flap, said tab being so folded and secured in place as to provide a free edge portion

which is spaced from the inner face of the cover flap and adapted to be tucked in back of said retaining flap when the cover flap is closed.

2. A match package of the book type comprising a card having a match retaining flap and a cover flap having its free end portion extended to cover said retaining flap, striker means on the outer face of the cover flap at said extended portion, a folded tab one fold of which is longer than the other, and means securing said tab to the inner face of said cover flap with the shorter fold against the cover flap and the longer fold in spaced relation thereto, said longer fold being adapted to be tucked in back of said retaining flap when the cover is closed. 10 15
